DESCRIPTION

FIG. 1 is a right front perspective view of our new design for a pair of spectacles;

FIG. 2 is a left front perspective view thereof;

FIG. 3 is a rear perspective view of the design shown in FIGS. 1 and 2.

NO AMENDMENTS HAVE BEEN MADE TO
THE PATENT.

REEXAMINATION CERTIFICATE
ISSUED UNDER 35 U.S.C. 307

AS A RESULT OF REEXAMINATION, IT HAS
5 BEEN DETERMINED THAT:

The patentability of claim 1 is confirmed.
